UNITED STATES PATENT OFFICE.

CLIFTON W. SHERMAN, OF BUFFALO, NEW YORK.

APPARATUS FOR MAKING CAR-WHEELS.

1,149,410.

Specification of Letters Patent. Patented Aug. 10, 1915.

Application filed November 9, 1914. Serial No. 870,985.

To all whom it may concern:

Be it known that I, CLIFTON W. SHERMAN, a citizen of the United States, residing at Buffalo, in the county of Erie and State 5 of New York, have invented new and useful Improvements in Apparatus for Making Car-Wheels, of which the following is a specification.

This invention relates to an apparatus for 10 making cast metal car wheels.

In car wheels as heretofore constructed the bearing face of the rim or tread frequently contained chill cracks which were caused by the metal tearing or bursting as 15 the casting contracted after being poured into the mold against a chill, thereby weakening the wheel and reducing its wearing capacity.

It is essential in car wheels that the metal 20 in the bearing face of the rim or tread and its flange be free from cracks, or the like, and that the maximum density or molecular affinity in the fiber or grain of this part of the wheel be attained in order that the wheel 25 may have the greatest strength and will resist the greatest amount of wear under the loads imposed on the same.

With these requisites in view it is the purpose of my invention to produce a machine 30 for making a car wheel in which the metal forming the bearing face of the tread or rim and its flange is compressed while still in a hot and more or less plastic state after being cast and thus increase the molecular affinity 35 or density of the metal in this region of the wheel and thereby render the same much stronger and durable than wheels constructed in the manner heretofore known.

In the accompanying drawings: Figure 1 40 is a vertical section of a cast metal car wheel and one form of apparatus embodying my invention. Fig. 2 is a horizontal section taken on line 2—2, Fig. 1. Fig. 3 is a fragmentary vertical section taken on line 3—3, Fig. 1. 45 Figs. 4 and 5 are detached top plan views of the primary and secondary sections of the rim or tread chill of the molding flask. Fig. 6 is a side elevation of one form of operating device for simultaneously shifting all parts 50 of the presser ring relatively to the chill sections of the flask. Fig. 7 is a top plan view of the same. Fig. 8 is a fragmentary vertical section showing another device for moving the presser ring relatively to the chill

sections. Fig. 9 is a side elevation thereof. 55 Fig. 10 is a vertical section showing still other means for moving the presser ring relatively to the chill sections.

Similar characters of reference indicate corresponding parts throughout the several 60 views.

Although the cast metal car wheel which is constructed by my improved method and apparatus may be varied in its details of construction that shown, for example in 65 Figs. 1, 2 and 8 comprises a central tubular hub A, an annular rim or tread B arranged concentrically around the hub and provided at its lower inner edge with an annular outwardly projecting flange b, and a supporting body or member arranged between the rim and hub and comprising a disk or plate C connected at its inner and outer edges with said hub and rim, inner brackets d connecting the inner part of the underside of 75 the plate with the hub, outer brackets e connecting the outer part of the underside of the plate with the rim, and an annular bead f arranged on the plate between the hub and rim and connecting the adjacent ends of said 80 brackets, said hub, rim, plate brackets and bead being formed integrally.

Referring to Figs. 1—5, 1 represents the bottom or mold board of a molding flask, 2 the drag or nowel which forms the lower 85 part of the flask, 3 the drag which forms the upper part of the flask, and 4, 5 the chill or chiller of metal arranged intermediate of the drag and cope and forming the side of the mold cavity 6 of the wheel 90 against which the bearing surface of the rim or tread is formed, as the metal is poured into the cavity through sprue 7 located centrally of the flask, as shown in Fig. 1, or any other suitable place. The chill is constructed in the form of a ring which is preferably divided into a plurality of primary sections 4 and a plurality of secondary sections 5 which alternate with each other. The several chill ring sections are arranged 100 between the drag and cope of the molding flask and the primary sections being comparatively long and the secondary sections comparatively short. Each of the primary chill ring sections has its opposite ends 8, 8 105 arranged parallel with each other and with a radial line drawn from the axis of the mold cavity of the wheel, but each of the

secondary chill ring sections 5 has its opposite ends 9, 9 converging inwardly relatively to each other and to a radial line drawn from the axis of the wheel mold cavity, so that each secondary chill ring section has the form of a V or wedge-shaped key. The opposing ends of the several chill sections engage with each other so as to form the annular outer wall of the mold cavity 10 against which the periphery or bearing face of the rim or tread of the wheel is formed as the molten metal is poured against the same.

While the metal is being poured into the mold cavity all of the chill ring sections are in their outermost positions and their inner sides are flush and form a continuous or even surface. After the mold cavity has been filled with molten metal and the latter 20 is still hot and in a more or less plastic or pasty condition, the primary chill ring sections are pressed inwardly under high power, preferably by mechanical means, so that metal in the rim or tread at the bearing 25 surface thereof is rendered more dense and a greater molecular affinity is established in the fiber or grain of the same. As the primary chill ring sections are forced inwardly they take up or compensate for any reduction 30 in the circumference of the rim or tread due to contraction or shrinkage of the wheel as the metal cools. The sectional chill ring is thus contractible and is adapted not only to the reduction in diameter or circumference 35 of the rim but by reason of the pressure applied to the primary chill ring sections the metal on the bearing surface of the wheel rim or tread is condensed or compacted. By this means the wheel rim is prevented 40 from bursting, tearing or cracking under pouring or peripheral contraction strains and the density of its fiber is increased, thereby increasing the strength of the wheel as well as its wearing qualities.

45 As the primary chill ring sections 4 move inwardly the secondary sections 5 remain stationary in order to permit this movement of the primary sections which is possible owing to the ends of each of the latter being 50 parallel with a radial line of the wheel mold. The inner surface presented by the secondary chill ring sections is comparatively small and reduced to a minimum consistent with practical working of the apparatus. Slight raises or fins may be left on 55 the bearing surface of the rim by reason of the primary chill ring sections moving radially independently of the secondary chill ring sections, such fins being readily removed when the rim of the wheel is ground for truing the same.

60 Various means may be employed for forcing the primary chill ring sections inward, those shown for example in Figs. 1-7, being 65 suitable and constructed as follows: The

outer side 10 of each primary chill ring section is inclined, preferably, from its upper end downwardly and outwardly to its lower end, as shown at the left of Fig. 1, while the outer side 11 of each of the secondary chill ring sections is vertical or parallel with the axis of the wheel mold, as shown at the right of this figure. 12 represents a presser ring which surrounds the several chill sections and which is provided on its inner side 70 with a plurality of alternating inclined faces 13 engaging with the inclined outer sides of the primary chill sections and vertical faces 14 engaging with the vertical outer faces 11 of the secondary chill sections. 80 Adjacent to each secondary chill section the presser ring is provided with a notch 15, preferably of dove-tail form which receives the correspondingly shaped outer part of the respective secondary chill sections, as 85 shown in Figs. 1 and 2. As the presser ring is moved downwardly the wedging engagement of its inclined faces 13 against the faces 10 of the primary chill sections forces the latter inwardly but the secondary chill 90 sections are unaffected and remain at rest. Upon raising the presser ring the primary chill sections are free to be again moved outwardly into their normal position. In order to maintain the chill sections in position 95 relatively to the presser, and guide these parts relatively to each other means are provided which preferably comprise upwardly tapering pins or studs 16, 17 arranged on the upper side of the presser ring and engaging with downwardly flaring openings or sockets 18 formed in lugs 19, 20 projecting outwardly from the upper ends, respectively, of the primary and secondary chill sections, as shown in Figs. 1, 4 and 5. As 100 the presser ring descends and moves the primary chill sections inwardly this is permitted by the tapering pins 16 withdrawing downwardly from the flaring openings 18 and when the presser ring rises the tapering 105 pins 16 upon entering the flaring openings 18 operate to retract the primary chill sections into their outer normal position. The pins 17 of the presser ring also withdraw in their descent from the openings 18 of the 110 secondary chill sections and again reenter the same when the presser ring rises but the function of these parts is merely to assist in keeping the secondary chill sections 115 in place relatively to the primary chill sections 120 and presser ring.

One of the various means which may be employed for moving the presser ring downwardly and upwardly comprises a plurality of right and left screws 21 each of which is 125 arranged vertically and engages its oppositely threaded ends with correspondingly threaded openings formed in lugs or brackets 22, 23 projecting laterally at suitable intervals from the cope and the presser ring, 130

as shown in Figs. 1 and 2. Each of these screws may be turned by providing the same with a flat sided shank 24 at its upper end suitable for receiving a wrench, crank or other tool. In order to hold the drag, cope and chill in the proper position relative to each other while the presser ring is being raised and lowered, means are provided which preferably comprise a plurality of 5 clamps each of which engages the jaw 25 at one end of the yoke 26 with the underside of the mold board while the screw 27 at the opposite end of the yoke engages with the top of the cope, as shown in Fig. 1. In 10 order to permit the primary chill sections to slide radially freely between the cope and drag the height of each of these chill sections is preferably slightly less than the distance between the cope and drag, as shown 15 at the left of Fig. 1, but the height of the secondary chill sections is the same as the distance between cope and drag, so that the 20 latter grip the secondary chill section but do not interfere with the free movement of 25 the primary chill sections. The cope, drag and presser ring are further held against lateral displacement by downwardly projecting centering pins 28 arranged on opposite sides of the cope and engaging with 30 openings 29 in the presser ring, and upwardly projecting centering pins 30 arranged on opposite sides of the drag and engaging with openings 31 in the presser 35 ring. For convenience in transporting or reversing the molding flask the presser ring is preferably provided on its opposite sides with trunnions 32, as shown in Figs. 1, 2, 6 and 7.

The screws 21 which shift the presser ring 40 are preferably operated simultaneously and this may be effected by the means which are shown in Figs. 6 and 7 and which comprise a portable frame 33, a plurality of upright spindles 60 journaled in said frame and 45 each provided at its lower end with a wrench socket 34 which receives the upper flat sided end of one of the screws 21, while its upper end is provided with a bevel gear wheel 35, and two shafts 61, 62 which are 50 journaled on said frame and are provided with bevel gear wheels 36 meshing with the wheels 35, and one of said shafts being provided with a crank 37.

If desired, the presser ring may be moved 55 downwardly by the means which are shown in Figs. 8 and 9 and which comprise an eccentric or cam 38 bearing against a lug 39 on the presser ring and provided with eccentric pins or trunnions 40, a handle 41 connected with said trunnions for turning the 60 cam, and links 42 connecting said trunnions with the bottom board of the molding flask. The same result may be obtained by mounting the flask as a whole on a wheeled truck 65 or carriage 42 which may be run upon the

base 44 of a hydraulic or fluid operated press which is provided with a standard 45 rising from the base 44, a working cylinder 46 arranged on the upper overhanging part of the standard, and a plunger 47 arranged in 70 said cylinder and provided at its lower end with a presser head 48 which bears against the upper side of said presser ring of the molding flask, as shown in Fig. 10. Upon admitting a pressure medium through the 75 pipe 49 or 50 into the upper or lower end of the cylinder, the plunger therein will be lowered or raised and by opening either of the pipes 51, 52 the spent pressure medium may be discharged from either end of the 80 cylinder.

By means of this press the presser rings of different molding flasks may be quickly and effectively operated in succession by bringing each truck carrying a flask in turn 85 between the base and plunger of the press.

I claim as my invention:

1. An apparatus for making cast car wheels comprising a molding flask having a drag forming the lower part of a mold, a 90 cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel and others of said sections having 95 their opposite ends converging inwardly relatively to each other and to a radial line of the wheel and engaging with the opposing ends of two parallel ended sections, and means for pressing said parallel ended sections inwardly. 100

2. An apparatus for making cast car wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel and others of said sections having 110 their opposite ends converging inwardly relatively to each other and to a radial line of the wheel and engaging with the opposing ends of two parallel ended sections, and means for pressing said parallel ended sections inwardly comprising an axially movable presser ring having a wedging engagement with the outer sides of the several parallel ended chill sections. 115

3. An apparatus for making cast car wheels comprising a molding flask having a drag forming the lower part of a mold, a cope forming the upper part of said mold, 130

- an annular metal chill forming the intermediate part of the mold and the outer wall of the cavity in which the rim is cast, said chill being divided into a plurality of sections 5 some of which sections have their opposite ends parallel with each other and with a radial line drawn from the axis of the wheel and others of said sections having their opposite ends converging inwardly relatively 10 to each other and to a radial line of the wheel and engaging with the opposing ends of two parallel ended sections, and means for pressing said parallel ended sections inwardly comprising an axially movable 15 presser ring having a wedging engagement with the outer sides of the several parallel ended chill sections, and means for actuating said presser ring.
4. An apparatus for making cast car 20 wheels comprising a molding flask having a drag forming the lower part of a mold, a cope forming the upper part of said mold, an annular metal chill forming the intermediate part of the mold and the outer wall of 25 the cavity in which the rim is cast, said chill being divided into a plurality of sections some of which sections have their opposite ends parallel with each other and with a radial line drawn from the axis of the wheel 30 and others of said sections having their opposite ends converging inwardly relatively to each other and to a radial line of the wheel and engaging with the opposing ends of two parallel ended sections, and each of 35 said parallel ended sections having an inclined outer side, and an axially movable presser ring having an inclined inner side which engages with the inclined outer side of the several parallel ended chill sections.
- 40 5. An apparatus for making cast car wheels comprising a molding flask having a drag forming the lower part of a mold, a cope forming the upper part of said mold, an annular metal chill forming the intermediate part of the mold and the outer wall 45 of the cavity in which the rim is cast, said chill being divided into a plurality of sections some of which sections have their opposite ends parallel with each other and 50 with a radial line drawn from the axis of the wheel and others of said sections having their opposite ends converging inwardly relatively to each other and to a radial line of the wheel and engaging with the opposing 55 ends of two parallel ended sections, and means for pressing said parallel ended sections inwardly comprising an axially movable presser ring having a wedging engagement with the outer sides of the several parallel ended chill sections, comprising right and left screw 60 threaded screws each of which engages with correspondingly threaded openings on said presser ring and one of said flask members.
6. An apparatus for making cast car 65 wheels comprising a molding flask having a drag forming the lower part of a mold, a cope forming the upper part of said mold, an annular metal chill forming the intermediate part of the mold and the outer wall of 70 the cavity in which the rim is cast, said chill being divided into a plurality of sections some of which sections have their opposite ends parallel with each other and with a radial line drawn from the axis of the wheel 75 and others of said sections having their opposite ends converging inwardly relatively to each other and to a radial line of the wheel and engaging with the opposing ends of two parallel ended sections, and means for 80 pressing said parallel ended sections inwardly comprising an axially movable presser ring having a wedging engagement with the outer sides of the several parallel ended chill sections, comprising right and left screw 85 threaded screws each of which engages with correspondingly threaded openings on said presser ring and one of said flask members.
7. An apparatus for making cast car 90 wheels comprising a molding flask having a drag forming the lower part of a mold, a cope forming the upper part of said mold, an annular metal chill forming the intermediate part of the mold and the outer wall 95 of the cavity in which the rim is cast, said chill being divided into a plurality of sections some of which sections have their opposite ends parallel with each other and with a radial line drawn from the axis of the wheel and others of said sections having 100 their opposite ends converging inwardly relatively to each other and to a radial line of the wheel and engaging with the opposing ends of two parallel ended sections, and means for 105 pressing said parallel ended sections inwardly, comprising an axially movable presser ring having a wedging engagement with the outer sides of the several parallel ended chill sections, comprising right and left screw 110 threaded screws each of which engages with correspondingly threaded openings on said presser ring and one of said flask members, and means for turning said screws simultaneously.
8. An apparatus for making cast car 115 wheels comprising a molding flask having a drag forming the lower part of a mold, a cope forming the upper part of said mold, an annular metal chill forming the intermediate part of the mold and the outer wall 120 of the cavity in which the rim is cast, said chill being divided into a plurality of sections some of which sections have their opposite ends parallel with each other and with a radial line drawn from the axis of the wheel and others of said sections having 125 their opposite ends converging inwardly relatively to each other and to a radial line

of the wheel and engaging with the opposing ends of two parallel ended sections, and means for pressing said parallel ended sections inwardly, comprising an axially movable presser ring having a wedging engagement with the outer sides of the several parallel ended chill sections, comprising right and left screw threaded screws each of which engages with correspondingly threaded openings on said presser ring and one of said flask members, and means for turning said screws simultaneously, comprising a plurality of spindles each of which is provided with a socket engaging one of said screws, a frame in which said spindles are journaled and gearing operatively connecting said spindles.

9. An apparatus for making cast car wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel and others of said sections having their opposite ends converging inwardly relatively to each other and to a radial line of the wheel and engaging with the opposing ends of two parallel ended sections, and means for pressing said parallel ended sections inwardly, comprising an axially movable presser ring having a wedging engagement with the outer sides of the several parallel ended chill sections, comprising right and left screw threaded screws each of which engages with correspondingly threaded openings on said presser ring and one of said flask members, and means for turning said screws simultaneously comprising a plurality of spindles each of which is provided with a socket engaging one of said screws, a frame in which said spindles are journaled, bevel gear wheels arranged on said spindles, and shafts which are journaled on said frame and which are provided with bevel gear wheels meshing with the gear wheels on said spindles and one of said shafts having a crank.

10. An apparatus for making cast car wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel and others of said sections having their opposite ends converging inwardly relatively

to each other and to a radial line of the wheel and engaging with the opposing ends of two parallel ended sections, clamps connecting said drag and cope, and means for pressing said parallel ended sections inwardly.

11. An apparatus for making cast car wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel and others of said sections having their opposite ends converging inwardly relatively to each other and to a radial line of the wheel and engaging with the opposing ends of two parallel ended sections, means for pressing said parallel ended sections inwardly comprising an axially movable presser ring having a wedging engagement with the outer sides of the several parallel ended chill sections, and means for guiding said ring and chill sections axially relatively to each other.

12. An apparatus for making cast car wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel and others of said sections having their opposite ends converging inwardly relatively to each other and to a radial line of the wheel and engaging with the opposing ends of two parallel ended sections, means for pressing said parallel ended sections inwardly comprising an axially movable presser ring having a wedging engagement with the outer sides of the several parallel ended chill sections, and means for guiding said ring and chill sections axially relatively to each other, comprising lugs projecting outwardly from said chill sections and each having an opening, and pins arranged on said ring and engaging with said openings.

13. An apparatus for making cast car wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite

ends parallel with each other, and with a radial line drawn from the axis of the wheel and others of said sections having their opposite ends converging inwardly relatively 5 to each other and to a radial line of the wheel and engaging with the opposing ends of the two parallel ended sections, means for pressing said parallel ended sections inwardly comprising an axially movable 10 presser ring having a wedging engagement with the outer sides of the several parallel ended chill sections, and means for guiding said ring and chill section axially relatively to each other, comprising lugs projecting 15 outwardly from said chill sections and each having an opening, and tapering pins arranged on said ring and engaging with said openings.

14. An apparatus for making cast car 20 wheels comprising a molding flask having a drag forming the lower part of a mold, a cope forming the upper part of said mold, an annular metal chill forming the intermediate part of the mold and the outer wall of 25 the cavity in which the rim is cast, said chill being divided into a plurality of sections some of which sections have their opposite ends parallel with each other and with a radial line drawn from the axis of the wheel 30 and others of said sections having their opposite ends converging inwardly relatively to each other and to a radial line of the wheel and engaging with the opposing ends of two parallel ended sections, and means 35 for pressing said parallel ended sections, inwardly, the outer sides of said parallel ended chill sections having inclined outer sides and said tapering chill sections having their outer sides parallel with the axis of the 40 wheel, and a presser ring provided on its inner side with inclined faces engaging with the inclined outer sides of said parallel ended chill sections.

15. An apparatus for making cast car 45 wheels comprising a molding flask having a drag forming the lower part of a mold, a cope forming the upper part of said mold, an annular metal chill forming the intermediate part of the mold and the outer wall of 50 the cavity in which the rim is cast, said chill being divided into a plurality of sections some of which sections have their opposite ends parallel with each other and with a radial line drawn from the axis of the wheel 55 and others of said sections having their opposite ends converging inwardly relatively to each other and to a radial line of the wheel and engaging with the opposing ends of two parallel ended sections, and means 60 for pressing said parallel ended sections inwardly, the outer sides of said parallel ended chill sections having inclined outer sides and said tapering chill sections having their outer sides parallel with the 65 axis of the wheel, and a presser ring pro-

vided on its inner side with inclined faces engaging with the inclined outer sides of said parallel ended chill sections, and also provided on its inner side with notches which receive the outer parts of said tapering 70 chill sections.

16. An apparatus for making cast car 75 wheels comprising a molding flask having a drag forming the lower part of a mold, a cope forming the upper part of said mold, an annular metal chill forming the intermediate part of the mold and the outer wall of the cavity in which the rim is cast, said chill being divided into a plurality of sections some of which sections have their opposite ends parallel with each other and with a radial line drawn from the axis of the wheel 80 and others of said sections having their opposite ends converging inwardly relatively to each other and to a radial line of the wheel and engaging with the opposing ends of two parallel ended sections, and means for pressing said parallel ended sections inwardly, the outer sides of said parallel ended chill sections having inclined outer sides and said tapering chill sections having their outer sides parallel with the axis of the wheel, and a presser ring provided on its inner side with inclined faces 85 engaging with the inclined outer sides of said parallel ended chill sections, and also provided on its inner side with dovetail notches which receive the outer parts of said tapering chill sections.

17. A molding apparatus comprising a 100 drag, a cope, a metal chill ring arranged between said cope and drag and comprising a plurality of sections some of which are movable radially, means for shifting said movable chill ring sections comprising a presser 105 ring having a wedging engagement with said movable chill ring sections, and means for guiding or centering said cope, drag and presser ring relatively to each other.

18. A molding apparatus comprising a 110 drag, a cope, a metal chill ring arranged between said cope and drag and comprising a plurality of sections some of which are movable radially, means for shifting said movable chill ring sections comprising a presser 115 ring having a wedging engagement with said movable chill ring sections, and means for guiding or centering said cope, drag and presser ring relatively to each other, comprising centering pins arranged on the cope 120 and projecting downwardly therefrom into openings in the presser ring, and centering pins arranged on the drag and projecting upwardly therefrom into openings in the presser ring.

19. A molding apparatus comprising a drag, a cope, a metal chill ring arranged between the drag and cope and comprising a plurality of relatively fixed sections and a plurality of radially movable sections which 130

alternate with the fixed sections, said fixed sections being gripped between the drag and cope while the movable sections are of slightly less height than the distance between the drag and cope so as to be freely movable between the same, and means for operating said movable chill ring sections.

Witness my hand this 3rd day of November, 1914.
